OVERFLOW PLATE FOR A BATHTUB OR THE LIKE

Stephen A. Young, Monticello, Ind.

Filed Jan. 15, 1959, Ser. No. 54,181

Term of patent 14 years

(Cl. D91—3)

Fig. 1

Fig. 2

Fig. 3

Fig. 5

I claim:

The ornamental design for an overflow plate for a bathtub or the like, substantially as shown.
